[57] CLAIM

The ornamental design for a ski boot walking accessory,
substantially as shown and described.

DESCRIPTION

FIG. 1 is a top and right front perspective view of a ski
boot walking accessory showing my new design;
FIG. 2 is a top plan view thereof;
FIG. 3 is a right side elevational view thereof, the left
side being a mirror image thereto;
FIG. 4 is a bottom plan view thereof;
FIG. 5 is a front elevational view thereof;
FIG. 6 is a rear elevational view thereof.
